UNITED STATES PATENT OFFICE.

DAVID P. JUDSON, OF PARNASSUS, PENNSYLVANIA.

GAS-BURNER.

1,391,062.

Specification of Letters Patent. Patented Sept. 20, 1921.

Application filed January 3, 1920. Serial No. 349,211.

To all whom it may concern:

Be it known that I, DAVID P. JUDSON, a citizen of the United States, residing at Parnassus, in the county of Westmoreland 5 and State of Pennsylvania, have invented certain new and useful Improvements in Gas-Burners, of which the following is a specification.

This invention relates to new and useful 10 improvements in gas burners, particularly to that type of gas burner adapted to be used in connection with boilers and furnaces, and the primary object thereof is to provide a burner of the type stated, in 15 a manner as hereinafter set forth, whereby the flames from the burner may be directed and distributed against the surface to be heated regardless of the contour of the interior of the combustion chamber in which 20 the burner is positioned, thereby assuring the economical and efficient use of gas in connection therewith.

Further objects of this invention are to provide a device of the character described 25 which is simple in its construction and arrangement, strong, durable and efficient in its use, readily assembled and demounted, adjustable, and comparatively inexpensive to manufacture.

To the accomplishment of these and such other objects as may hereinafter appear, the invention consists of the novel construction, combination and arrangement of parts herein specifically described and illustrated 35 in the accompanying drawing, wherein is shown an embodiment of the invention, but it is to be understood that the device shown is merely illustrative and that various changes in the form, proportion and minor 40 details of construction may be resorted to, without departing from the principle or sacrificing any of the advantages of the invention, which come within the scope of the claims hereunto appended.

In the drawing forming a portion of this 45 specification and wherein like numerals of reference designate corresponding parts throughout the several views:

Figure 1 is a transverse sectional elevation of a gas burner in accordance with this 50 invention.

Fig. 2 is a longitudinal sectional view thereof.

Fig. 3 is an elevation of the mixer ele- 55 ment.

Fig. 4 is a top plan view of a modification.

Referring to Figs. 1 to 3, of the drawing, the burner comprises a body portion 1 formed of an elongated hollow cylindrical 60 member, closed at one end by a cap 2, and adapted to have its other end connected with a gas supply pipe, not shown; the connection being in any manner desired.

The body portion 1 is provided with a 65 plurality of radially disposed openings 3, having threaded walls and these latter are employed for connecting a mixer element or a closure plug 4 to the body portion. The 70 number and arrangement of the openings 3, in the body portion 1, may be as desired to best meet conditions found in practice.

The mixer element comprises an apertured mixer pin 5, having a shank 6 formed with a threaded periphery and the shoulder 75 portion 7. The threaded shank 6 connects with the threaded wall of an opening 3, whereby the mixer pin 5 is secured to the body portion 1. The mixer pin 5 communicates with the interior of the body portion 80 1, as clearly shown in Figs. 1 and 2, of the drawing. Mounted upon the shoulder portion 7 and surrounding the mixer pin 5, as well as being secured to the latter by a set screw 8, is a collar 9, the latter having 85 formed integral with its periphery a pair of outwardly projecting opposed arms 10 which terminate in the periphery of a band 11, the latter being spaced from the collar 9 to provide an inlet for air to the inner 90 end of the burner tube 12, which extends through the band 11 and is adjustably connected with the latter by a set screw 13.

The burner tubes 12 are elongated and each of a length whereby the flame at the 95 outer end of the tube will be positioned to properly and efficiently contact with the surface which is to be heated.

The tubes 12 are radially disposed and 100 may be of different lengths to best meet conditions encountered. When tubes 12 are not connected to certain of the openings 3, these latter openings are closed by the plugs 4 to prevent the escape of gas therethrough.

The outer ends of the tubes 12 have peripheral threads for connecting therewith a burner tip 14, the latter being T-shaped and has the horizontal leg thereof closed by plugs 15, and the said horizontal leg of the tip 14 is furthermore provided with spaced 110

transverse slots 16 communicating with the burner tube 12. The tips 14 are used only when low pressure gas is employed. When high pressure gas is used the burner tubes 5 12 are employed without the tips 14.

The burner tubes 12 are so set up and of such lengths that they will extend in proximity to the surface to be heated so that the flame will come in direct contact with such 10 surface and quickly and intensely heat same. The burner is employed primarily in connection with portable boilers and furnaces, but it is obvious that the burner can be employed for any purposes wherein it is found 15 applicable.

In Fig. 1 of the drawing the body portion of the burner is shown as formed of a single hollow cylindrical member, while in the modified form, shown in Fig. 4, the body 20 portion is illustrated as consisting of a pair of hollow cylindrical members 17 and 18, each having one end closed by the caps 19, and its other end attached to an elbow coupling 20. Secured to the elbow couplings 25 20 is a connecting or conducting pipe 21, which has attached thereto a gas supply pipe 22. The form of burner tube, burner tip, mixer element, and closure plug, is the same as that shown in Fig. 1, and such elements of the structure are indicated at 23, 30 24, 25 and 26, respectively.

It is obvious that the body portion can consist of any number of hollow cylindrical members, that is to say, one or more.

35 What I claim is:

1. A gas burner comprising a hollow cylindrical element adapted to be connected with a gas supply and having a plurality of openings, a vertically disposed and a plurality of upwardly inclined mixer elements secured in said openings, and a burner tube mounted in each of the mixer elements and extending in the same direction throughout as its respective mixer element.

45 2. A gas burner comprising a hollow cylindrical element adapted to be connected with a gas supply and having a plurality of openings, a vertically disposed and a plurality

80 of upwardly inclined mixer elements secured in said openings, a burner tube 50 mounted in each of the mixer elements and extending in the same direction throughout as its respective mixer elements, each of said mixer elements provided at its outer end with means whereby the tube carried thereby can be lengthwise adjusted relatively thereto.

3. A gas burner comprising an elongated hollow cylindrical member adapted to be connected with a gas supply and having a series of openings, a vertically disposed and a plurality of upwardly inclined mixer elements secured in said openings, said inclined mixer elements disposed on opposite sides of said member, and a burner tube mounted in 60 each of the mixer elements and extending in the same direction throughout as its respective mixer element.

4. A gas burner comprising a hollow element adapted to communicate with a gas supply and provided with openings disposed vertically and at an upward inclination, vertically disposed and upwardly inclined mixer elements secured in said openings, vertically disposed and upwardly inclined 75 burner tubes mounted in said elements, and said elements at their outer ends provided with means whereby the burner tubes can be lengthwise adjusted within and relative to said elements.

5. A gas burner comprising a hollow element adapted to communicate with a gas supply and provided with openings disposed vertically and at an upward inclination, vertically disposed and upwardly inclined 85 mixer elements secured in said openings, vertically disposed and upwardly inclined burner tubes mounted in said elements, said elements provided with means whereby the burner tubes can be lengthwise adjusted 90 within and relative to said elements, and T-shaped slotted tips mounted on the outer ends of said tubes.

80 In testimony whereof I affix my signature.

DAVID P. JUDSON.
